UNITED STATES PATENT OFFICE

ERNEST M. FRITZ, OF CHICAGO, ILLINOIS

MUSIC LEAF TURNER

Application filed August 24, 1929. Serial No. 388,249.

My invention relates to music leaf turners, its primary object being the provision of a novel form of foot for engaging the music sheets to be turned.

More specifically, it is my object to provide a foot having a live rubber engaging surface of novel form for effectively engaging the sheets.

Another of my objects is the provision of a leg for supporting the foot, the leg being both yieldable and adjustable.

Another of my objects is the provision of an arm for actuating the leg and foot, the arm being adjustable in length.

Another object which I have in view is the provision of a simple actuating mechanism for swinging the arm through an arc and for gradually lifting the arm at the same time.

While my music leaf turner is designed primarily for efficiency, my object has been to make it in the simplest possible form so that it may be constructed at the lowest cost consistent with efficiency.

Having in view these objects and others which will be pointed out in the following description, I will now refer to the drawings, in which

Figure 1 is a view in perspective of the operative portions of my music leaf turner, a portion of the casing being broken away to disclose the turning mechanism.

Figure 2 is a perspective view of the music leaf turner as seen from the side facing the operator.

Figure 3 is a view in perspective of the arm and showing particularly the adjusting mechanism for the arm.

Figure 4 is an elevational view showing the foot and showing particularly the various leg members.

Figures 5 to 8 inclusive are perspective views showing the action of the leaf turner at different stages.

Figure 9 is a view in elevation of the lower end of the leg and of the foot immediately before it exerts a gripping action on the leaf.

Figure 10 is a view similar to Figure 9 but showing the foot in its full gripping action.

The foot consists of a piece of live rubber 10 which is clamped between two metallic

plates 11, the plates being pivotally connected at 12 to the leg. The rubber foot 10 is provided with a number of toes 13 arranged in the form shown best in Figure 4. A pin 14 passing through the rubber foot 10 engages the upper edges of the plates 11 to prevent accidental slipping of the foot 10 relative to the plates. The two plates 11 are joined by an abutment 15 which limits the pivotal movement of the foot on the leg.

The leg includes an upper portion 16 and a lower portion 17 with a coil spring 18. The upper leg portion 16 is hollow for receiving the spring 18. The lower leg portion 17 is slidable within the upper leg portion 16 against the compression of the spring 18. The upper leg portion 16 is provided with a pin 19 passing through the slot 20 of the lower leg portion 17, the purpose of the pin and slot connection being to limit the sliding movements of the lower leg portion.

The leg is adjustably secured in the looped end portion 21 of the arms. This adjustment is made by means of a set screw 22 and its purpose is to take care of pads of sheet music of varying thicknesses. When the pad is relatively thick, the leg is raised in the collar 21 and when the pad is relatively thin the leg may be lowered. The arm itself has two adjustments. The main portion 23 of the arm is slidable at one end into the collar portion of the end member 21 and it is slidable at its other end into the arm member 24. The portion 23 is preferably made from steel or other relatively rigid material and it is provided in its upper surface with a plurality of sockets 25 as best shown in Figure 3. For holding the member 23 in any desired position of adjustment in the collar member 21, I provide a set screw 26 which engages the upper surface of the member 23. The member 23 is also slidably adjustable in the member 24 which is provided with a spring 27 having a pin 28 which is adapted to seat in one of the sockets 25. It will thus be apparent that the arm may be lengthened or shortened by releasing the spring 27 and sliding the member 23 out of or into the member 24.

The purpose of this, of course, is to take care of music sheets of various widths.

The member 24 has a collar portion 29 at its inner end surrounding the actuating rock shaft 30. The arm 24 is thus held on the rock shaft 30 by means of the set screw 31 which permits arcuate adjustment of the arm on the rock shaft.

The rock shaft 30 is provided with a pulley 32 and with a barrel 33. The pulley 32 has secured thereto a flexible member 34 whereby tension may be applied to the flexible member 34 to rotate the pulley 32 and with it the shaft 30. For restoring these parts to their normal position I provide a coil spring 35. It is necessary, however, for efficient operation that the foot be made to disengage the sheet as soon as the sheet has been turned. This is best accomplished by lifting the foot when the sheet has been sufficiently turned for its own weight to carry 20 to the end of the turning movement. For raising the shaft 30 and with it the foot 10, I have provided a cam edge 35 on the barrel 33, the cam edge riding on the fixed abutment 36.

25 The support for the music leaf turner comprises a box-like structure 37 which encloses the operating parts for the shaft 30. The shaft 30 is in this housing 37 which also supports the abutment 36. The housing 37 is provided with two lateral wings 38 projecting in opposite directions and lying in the same plane. These wings constitute the means for securing the music leaf turner to a music stand or to the musical instrument. 30 35 The housing 37 is further provided with a slot 39 for the flexible member 34.

In operation, the pad of sheet music is positioned underneath the foot of the music leaf turner, the music leaf turner having 40 been secured to the music stand or to the musical instrument. The leg is then raised or lowered to provide the proper adjustment for the thickness of the pad of sheet music. The arm is then extended or retracted according to the width of the music sheets. By 45 then applying tension to the flexible member 34, the foot 10 is dragged over the pad of sheet music and since the live rubber of the foot engages the top sheet in much the same manner that a moist finger would engage it, the sheet is dragged until it passes the perpendicular with respect to the hinge. During 50 the forward movement of the foot there is a pivotal movement about the pivot 12 until the foot 10 secures the maximum grip on the sheet. During the forward movement the cam 35 causes the foot to be gradually raised so as to finally release the sheet where it is allowed to fall the rest of the distance. The 55 action and movement thus resemble in every respect the action and movement of a moist finger when used for the same purpose.

60 The music leaf turner may be actuated by applying tension to the flexible member 34 in any desired manner. The flexible member

34 will cause the swinging of the arm 24 through an arcuate path carrying with it the leg and the foot 10. Owing to the position of the pivot 12, the forward extremity of the foot rests somewhat lightly on the music 70 sheet, the pressure being governed by the tension of the spring 18 and the adjustment of the leg. The foot 10 will frictionally engage the music sheet so that the forward movement will cause a slight drag which will 75 tend to move the foot about its pivotal connection 12 with the leg. As the point of contact of the foot 10 approaches more nearly the vertical position with respect to the pivot 12, the distance between the pivot 12 and the 80 point of contact of the foot increases and this thereby increases the friction of the foot due to the increase in pressure.

Having thus described my invention in such full, clear, and exact terms that its construction and operation will be readily understood by others skilled in the art to which it pertains, what I claim as new and desire to secure by Letters Patent of the United States is:

1. In a music leaf turner, an arm adapted for arcuate swinging movement in an inclined plane, a leg depending from said arm at the free extremity thereof, and an elongated foot of live rubber pivotally secured at its rear extremity to said leg at the lower extremity thereof.

2. In a music leaf turner, an arm adapted for arcuate swinging movement in an inclined plane, a leg depending from said arm at the free extremity thereof, an elongated foot having a substantially spiral cam shaped gripping surface, a pivot pin passing through the lower extremity of said leg and through the rear portion of said foot, and an abutment for limiting the pivotal movement of said foot on said leg.

3. In a music leaf turner, an arm and manually operable means for swinging said arm through an arcuate path, a leg depending from said arm and an elongated foot pivotally secured to said leg, said foot having a substantially spiral cam-shaped rubbing surface extending forwardly of the pivotal connection thereof whereby the friction of said rubbing surface will retard the movement thereof and thus cause said foot to move on its pivotal axis to increase the pressure thereof on the sheet of music during the arcuate movement of said cam.

4. In a music leaf turner, an arm and manually operable means for swinging said arm through an arcuate path, a leg depending from said arm and an elongated foot pivotally secured to said leg, said foot having a substantially spiral cam-shaped rubbing surface extending forwardly of the pivotal connection thereof whereby the friction of said rubbing surface will retard the movement thereof and thus cause said foot to move on

its pivotal axis to increase the pressure thereof on the sheet of music during the arcuate movement of said arm, and means for limiting the pivotal movement of said foot.

- 5 5. In a music leaf turner, an arm movable in an arcuate path, a compressible leg depending from said arm, and a foot pivotally secured to said leg, said foot having a spiral cam-shaped rubbing surface beginning at a 10 point directly beneath said leg and extending forwardly therefrom whereby the friction of said foot on the sheet of music will result in the pivotal movement of said foot to increase the compression of said leg and 15 to increase the friction of said foot on the sheet of music.

In testimony whereof I affix my signature.
ERNEST M. FRITZ.
